UNITED STATES PATENT OFFICE

2,174,557

TAPE PROJECTION DEVICE

David Franklin, Chicago, Ill., assignor, by mesne assignments, to Trans-Lux Movie Ticker Corporation, New York, N. Y., a corporation of Delaware

Application July 29, 1935, Serial No. 33,730
Renewed September 12, 1938

8 Claims. (Cl. 88—24)

This invention relates to a projector for ticker tape or the like.

The invention has particularly to do with a device of few parts and of great reliability for moving a ticker tape periodically as it comes from a ticker machine across a beam of light to allow projection of characters on the tape upon a screen.

Tape projection machines have heretofore pulled the tape across a glass table through which a beam of light was projected. The pulling device made firm contact with the tape, and a switch or other mechanism was operated by an arm actuated by a loop of tape to control the pulling device and prevent breakage of the tape. In spite of the complicated mechanism tape breakage occurred. The devices had many complicated parts and were frequently out of order.

The present invention avoids such difficulties and provides new reliability of performance.

The objects of the invention include among others, the provision of the following:

An improved tape projection device;
Unique tape holding means;
An improved tape moving drive;
Improved means for automatically moving a periodically fed tape; and

Improved automatic means for a tape moving mechanism.

These objects, and other objects which will hereinafter appear, are obtained by the novel arrangement and construction of elements hereinafter described and claimed. A machine embodying the invention is illustrated in the accompanying single sheet of drawings hereby made a part of this application and in which;

Figure 1 is a vertical longitudinal section through a tape projection machine embodying the present invention;

Figure 2 is a cross section of the device of Figure 1 on line 2—2 of Figure 1; and

Figure 3 is a view of the tape holding mechanism of the same machine on line 3—3 of Figure 2.

The present embodiment of the invention is housed in a box or container 10 which may be of wood or metal or other suitable material. The box 10 is rectangular in plan. In the top of the box near one end thereof is a tape trough 11 having a bottom portion 12 slightly wider than the tape which is intended to pass therethrough. Above the bottom portion 12 the sides of the trough 11 may flare outwardly. The trough 11 extends entirely across the short dimension of the box and is open at the ends. A portion of the floor of the bottom portion 12 of the trough comprises a plano-convex lens 13, plane face upward. Guide ledges, not shown, may extend the length of the trough just above lens 13, protruding a short distance into the

trough. The ledges help to prevent the tape from buckling upwards.

The tape is moved across the lens 13 by a motor 14, which may be of any type such as the ordinary rapidly turning electric motor with a speed reduction device 15, or a low constant speed motor of the type commonly known as a Telechron motor, without speed reduction. Motor 14 may be secured to the bottom of box 10 by a bracket 16. A shaft 17 extends from the speed reducer 15 to below the floor of the trough 11. A tape moving roller 18 is mounted on shaft 17 and extends substantially across the floor of the trough. The floor of the trough is cut away at 19 and roller 18 extends through the aperture thus made so that the top face of the roller is approximately level with the top surface of the bottom of the trough.

The roller 18 may be smooth or may be lightly corrugated or knurled. It should be of a material such as metal which will not pull heavily on a tape in contact with the top of the roller. Roller 18 lies crosswise of trough 11 and has its plane of rotation parallel to the long axis of trough 11.

Directly above the center of roller 18 is an idler pressure wheel 20. Wheel 20 is mounted on a pin 21 which is carried at right angles to an arm 22 and extends at right angles to the long axis of trough 11. Arm 22 is parallel to long axis of trough 11 and is mounted on a shaft 23. Shaft 23 has pointed ends. One pointed end rests in a socket in one wall of trough 11. The other end of shaft 23 is carried by a socket in the end of an adjusting screw 31. Shaft 23 is threaded at the ends and a plurality of spacing washers 38 locate the arm 22 in a selected position on the shaft. The position is changed by moving washers from one side to the other. Nuts 39 hold the washers 38 in place. Where desired the washers may be dispensed with and the shaft 23 threaded its whole length, the nuts 39 then holding the said arm 22 directly. The position of the arm is changed by changing the positions of the nuts. Wheel 20 is held against roller 18 only by its own weight and the weight of pin 21 and arm 22. Wheel 20, pin 21 and arm 22 are of light construction to avoid heavy contact between wheel 20 and roller 18. The wheel 20 has a narrow periphery to enable it to pass between rows of characters on a tape without smearing them.

Below the lens 13 at the bottom of trough 11 is a mirror 25. A projection type lamp 26 and a condenser 27, which may include a water cooling chamber 27a, are placed to direct a beam of light against mirror 25. Mirror 25 is angularly set on a bracket 28 and reflects the beam of light upward through lens 13. A ventilator 29 may be placed in the top of the box 10 above

the lamp 26, and ventilating holes 30 may be cut in the wall of box 10 adjacent lamp 26. A concave mirror 31 may be placed behind lamp 26. Lamp 26 may be tilted to a position at a right angle to the axis of the condenser 27.

5 An arm 32 may be secured to the side wall of box 10. The top of arm 32 coincides with the top of the floor of trough 11. Arm 32 is at the side of box 10 away from roller 18. The face 10 of arm 32 is level near the wall of box 10 and further away from the box rises slightly and then curves downward. At the outer end of arm 32 a cavity 33 is provided to receive a fine wire brush 34 or a piece of tinsel or the like, the ends of the 15 bristles of which extend slightly beyond the end of arm 32.

A ticker tape 35 is fed into the bottom part 12 of groove 11 at the side near roller 18. The tape 35 is passed between roller 18 and wheel 20 and 20 is allowed to slide across lens 13 on the floor of the trough. Ticker tape 35 comes from a ticker machine which prints stock quotations or other data on the tape. The movement of the tape from the ticker machine is intermittent.

25 Motor 14 is turned on, causing roller 18 to re-volve. The speed of rotation of roller 18 is such that its periphery moves at a speed approximately equal to the speed at which tape 35 comes from the ticker machine in its periods of motion. 30 Motor 14 and roller 18 operate continuously. While tape 35 is moving from the ticker machine roller 20 presses the tape 35 against roller 18 and the peripheral movement of roller 18 is transmitted to the tape 35, which moves across lens 35 13. The tape 35 is pushed and not pulled across lens 13 and out of the box over arm 32. The con-formation of arm 32 is such that it accommodates the upward loop of the tape caused by the end of the tape dropping down from the end of the 40 arm. The weight of the length of tape below arm 32 may create a slight pull on the tape within the trough, aiding in the movement of the tape.

45 The wire brush or tinsel 34 picks up charges of static electricity from the moving tape and keeps the tape from sticking to the articles of furniture or to the machine. Brush 34 may be grounded to carry away the charges of electricity.

When the tape 35 stops moving from the ticker machine the continued rotation of roller 18 50 tightens the tape between the roller and the ticker machine. The pressure of wheel 20, however, is such that while the movement of roller 18 is communicated to the tape when the tape is free to move the roller 18, it merely slides under the tape 35 when the movement of the tape from the ticker machine is stopped. The selected light 55 pressure of wheel 20 provides an automatic clutch mechanism which allows the tape to move or stop according to the operation of the ticker machine and without danger of breaking the tape, while 60 roller 18 continues to turn. The tape, while thin and flexible, is readily pushed by roller 18 across lens 13 and out of the trough. The tape lies flat on lens 13 because there is nothing to hold it away therefrom.

65 An ordinary projection lens or a series of lenses 36 focuses the image of the tape 35 upon a screen. The images of the characters on the tape move across a screen while the tape is moving and stop when the tape is stopped.

70 Inasmuch as the motor and roller of the present device are allowed to operate constantly, no delicate switch mechanism is required. The wheel 20 and its carrying arms and shafts can not 75 get out of order unless broken by impact or some

other accident and then may be readily repaired or replaced. The lamp 26 may be readily replaced, as by removing ventilator 29, or through a door (not shown) into the box. The simplicity and the lack of delicate moving parts allows a high degree of reliability.

What is claimed as new and is desired to be secured by Letters Patent of the United States is:

1. In a device for converting the intermittent feed of a tape as it is being supplied into a smooth uniform feed at the light aperture of a projection machine, the combination of a horizontally extending, extensive surface engaging support for engaging one face of the tape throughout both before arriving at the light aperture, while at the light aperture and after leaving the light aperture including an anterior area, an intermediate area forming a light aperture and a posterior area, the anterior area being interrupted to provide an opening, a continuously operating tape pulling roller having its axis extending transverse to and below said support with its periphery emerging at said opening and passing through a plane tangential thereto and parallel to and in alinement with the level of said support to facilitate intimate engagement of said tape pulling roller with the tape, and a pressure wheel disposed to rest on the tape and press the tape into feeding relation with said tape pulling roller, said tape pulling roller and pressure wheel being disposed in the anterior area of said support not only to push the tape across said support as the tape is supplied thereto but also to iron out the vibrations transmitted to the tape when being supplied to said support.

2. In a device for converting the intermittent feed of a tape as it is being supplied into a smooth uniform feed at the light aperture of a projection machine, the combination of a horizontally extending, extensive surface engaging support for engaging one face of the tape throughout both before arriving at the light aperture, while at the light aperture and after leaving the light aperture including an anterior area, an intermediate area forming a light aperture and a posterior area, the anterior area being interrupted to provide an opening, a continuously operating tape pulling roller having its axis extending transverse to and below said support with its periphery emerging at said opening and passing through a plane tangential thereto and parallel to and in alinement with the level of said support to facilitate intimate engagement of said tape pulling roller with the tape, a pressure wheel disposed to rest on the tape and press the tape into feeding relation with said tape pulling roller, said tape pulling roller and pressure wheel being disposed in the anterior area of said support not only to push the tape across said support as the tape is supplied thereto but also to iron out the vibrations transmitted to the tape when being supplied to said support, and an upwardly curved convex supporting face forming a continuation of said posterior area and terminating in a downwardly extending area to conform to the natural curve in the tape when passing from a horizontal plane to a vertically extending suspended position and thereby protect the tape at the light aperture from bulging upwardly away from the supporting surface.

3. In a device for converting the intermittent feed of a tape as it is being supplied into a smooth uniform feed at the light aperture of a projection machine, the combination of a horizontally ex-

tending, extensive surface engaging support for engaging one face of the tape throughout both before arriving at the light aperture, while at the light aperture and after leaving the light aperture including an anterior area, an intermediate area forming a light aperture and a posterior area, the anterior area being interrupted to provide an opening, a continuously operating tape pulling roller having its axis extending transverse to and below said support with its periphery emerging at said opening and passing through a plane tangential thereto and parallel to and in alinement with the level of said support to facilitate intimate engagement of said tape pulling roller with the tape, a pressure wheel disposed to rest on the tape and press the tape into feeding relation with said tape pulling roller, said tape pulling roller and pressure wheel being disposed in the anterior area of said support not only to push the tape across said support as the tape is supplied thereto but also to iron out the vibrations transmitted to the tape when being supplied to said support, an upwardly curved convex supporting face forming a continuation of said posterior area and terminating in a downwardly extending area to conform to the natural curve in the tape when passing from a horizontal plane to a vertically extending suspended position and thereby protect the tape at the light aperture from bulging upwardly away from the supporting surface, and static discharge means engaging the tape at the discharge end of the posterior continuation to dissipate any static in the tape that might interfere with the smooth uniform discharge of the tape from said posterior continuation.

4. A tape projection device comprising a tape guiding trough, and a transparent support in the bottom of said trough through which light is transmitted to the tape, said support having an upwardly facing horizontally extending face, said trough having side walls flaring upwardly and outwardly from said supporting face to facilitate locating the tape on said transparent support.

5. A tape projection device comprising a transparent support having a horizontally supporting face through which light is transmitted to the tape supported by said support, a continuously operating tape puller having its axis extending transverse to and below said support with its periphery passing through a plane tangential thereto and parallel to and in alinement with the level of said supporting face to facilitate intimate engagement of said tape puller with the tape, a shaft rotatably mounted above and transverse to the path of movement of the tape, an arm secured to said shaft, a pressure wheel rotatably mounted at the free end of said arm, washers disposed to either side of said arm on said shaft to center said arm and thereby said wheel to engage the tape in a predetermined path between rows of printed matter, and nuts screw threadedly connected on said shaft to either side of said washers movable to adjust the position of such washers.

6. A tape projection device comprising a horizontally extending tape supporting light aperture, a tape puller having its axis extending transverse to and below said support with its periphery passing through a plane tangential thereto and parallel to and in alinement with the level of said supporting face to facilitate intimate engagement of said tape puller with the tape, a shaft rotatably mounted above and transverse to the path of

movement of the tape, an arm secured to said shaft, a pressure wheel rotatably mounted at the free end of said arm, washers disposed to either side of said arm on said shaft to center said arm and thereby said wheel to engage the tape in a predetermined path between rows of printed matter, and nuts screw threadedly connected on said shaft to either side of said washers movable to adjust the position of such washers.

7. In a device for converting the intermittent feed of a tape as it is being supplied into a smooth uniform feed at the light aperture of a projection machine, the combination of a horizontally extending, extensive surface engaging support for engaging one face of the tape throughout both before arriving at the light aperture, while at the light aperture and after leaving the light aperture including an anterior area, an intermediate area forming a light aperture and a posterior area, the anterior area being interrupted to provide an opening, a tape pulling roller, a pressure wheel disposed to rest on the tape and press the tape into feeding relation with said tape pulling roller, said tape pulling roller and pressure wheel being disposed at the anterior area of said support not only to push the tape across said support as the tape is supplied thereto but also to iron out the vibrations transmitted to the tape when being supplied to said support, and an upwardly curved convex supporting face forming a continuation of said posterior area and terminating in a downwardly extending area to conform to the natural curve in the tape when passing from a horizontal plane to a vertically extending suspended position and thereby protect the tape at the light aperture from bulging upwardly away from the supporting surface.

8. In a device for converting the intermittent feed of a tape as it is being supplied into a smooth uniform feed at the light aperture of a projection machine, the combination of a horizontally extending, extensive surface engaging support for engaging one face of the tape throughout both before arriving at the light aperture, while at the light aperture and after leaving the light aperture including an anterior area, an intermediate area forming a light aperture and a posterior area, the anterior area being interrupted to provide an opening, a tape pulling roller, a pressure wheel disposed to rest on the tape and press the tape into feeding relation with said tape pulling roller, said tape pulling roller and pressure wheel being disposed at the anterior area of said support not only to push the tape across said support as the tape is supplied thereto but also to iron out the vibrations transmitted to the tape when being supplied to said support, an upwardly curved convex supporting face forming a continuation of said posterior area and terminating in a downwardly extending area to conform to the natural curve in the tape when passing from a horizontal plane to a vertically extending suspended position and thereby protect the tape at the light aperture from bulging upwardly away from the supporting surface, and static discharge means engaging the tape at the discharge end of the posterior continuation to dissipate any static in the tape that might interfere with the smooth uniform discharge of the tape from said posterior continuation.

DAVID FRANKLIN.
